UNITED STATES PATENT OFFICE.

PIERRE MAURICE JAUVERT, OF TOULON, FRANCE.

REFRIGERATING APPARATUS.

Application filed March 31, 1924, Serial No. 703,243, and in France March 31, 1923.

My invention relates to refrigerating plants which comprise a circulation of a cold-conveying fluid which can be non-freezing-liquid, or a non-liquefiable gaseous fluid, whose temperature becomes reduced during the circulation, and which is then supplied to suitable piping for the refrigeration of the various rooms or spaces to be cooled.

10 This type of installation comprises, in a closed circuit, a compressor for the suction and the compression of a liquefiable gaseous fluid which will be herein designated as the refrigerating fluid; a condenser consisting of a temperature-exchanging device in which the compressed fluid from the said compressor becomes liquefied by cooling in contact with a cold liquid circulation (water as a rule); an evaporator constituted by a 15 temperature-exchanging device wherein the liquid refrigerating fluid from the condenser is caused to evaporate by the effect of the suction of the compressor and withdraws the heat necessary for its evaporation. This fluid, as stated hereinabove, can be a non-freezing brine or in other cases air, and when thus cooled the said fluid is supplied to the piping for the refrigeration of the 20 several rooms or spaces to be cooled.

My said invention has for its object the regulation of the production of cold in a refrigerating plant of this type by means of the change of volume of a liquid when congealing.

25 In an installation of this class, the amount of cold to be brought by the said cold-conveying liquid into the rooms or spaces to be cooled, and hence the rate of evaporation 30 of the refrigerating fluid in the evaporator, should be at all times proportional to the momentary requirements of the said rooms as concerns the temperature. For instance, in an ice-making plant, the difference in 35 temperature, at the end of the operation between the water subjected to freezing and the cold-conveying fluid is much less than at the beginning of the operation, so that the amount of calories which can be taken 40 away by the said fluid per unit of time will thus be reduced; it is therefore advisable to diminish the production of cold in order to obviate the introduction of non-evaporated refrigerating liquid into the compressor, since this may cause damage and will

at all events reduce the efficiency of the plant.

A positive indication that all the cold produced by the evaporator is absorbed by the cold-conveying fluid and used in the rooms 45 or spaces to be cooled, is afforded when frost is seen upon the suction piping of the refrigerating fluid of the evaporator; but the frost will in this event appear only along a short distance, at the outlet of the 50 evaporator.

The automatic regulator of the production of cold consists of a valve mounted on the refrigerating fluid piping between the condenser and the evaporator; said valve is 55 controlled by the gradual increase in volume of a congealable liquid contained in a control device whereof one portion surrounds the suction tube serving for the withdrawal of the refrigerating liquid from the evaporator. When the liquid thus withdrawn becomes too cold, the liquid in the said control device will be frozen along the greater part of the length thereof, and this will 60 reduce the flow of the refrigerating liquid 65 between the condenser and the evaporator.

The following description and appended drawing which are given by way of example relate to a constructional form of the said apparatus, the latter being shown in vertical 70 axial section.

The said refrigerating arrangement comprises a vertical supporting frame 1 having bored therein at the upper part various radial cylinders such as 2, 3 which are disposed about a central portion 4 constituting a suction chamber. The lower extension 5 is traversed by the motor shaft 6 which is provided at this point with a suitable fluid-tight packing, not shown. At the lower end 95 of the shaft is mounted the driving pulley 7. Upon the upper end of the said shaft is disposed the crank 8 coacting with the pistons 9, 10 through the medium of suitable piston rods. Said pistons are provided 100 with valves not shown which open during the suction stroke and close during the discharge stroke. The main frame 1 comprises a flat circular portion situated below the said cylinders, and upon which is mounted a vertical cylindrical casing 14. Upon the inner wall of said casing is disposed the condenser, comprising an annular space 15 disposed between two surfaces of the respective flat 105 annular elements 16, 17 in coaxial position; 110

the said elements are filled with granulated lead for insulating purposes. The upper part of the condenser 15 is connected by the tube 18 with a collector 19 communicating 5 with the discharge tubes 20 of the compressor cylinders. The condenser chamber 15 is surrounded by a jacket 21, which is supplied at the bottom with circulating water from conduit 22 and discharges the same at 10 the top through the pipe 23 into the casing 14 from which it is discharged through a pipe 24 opening at the upper part of said casing. The evaporator surrounds the said casing, which is covered for this purpose 15 with an insulating coating 25; the said evaporator—in the same manner as the condenser—consists of an annular chamber 26 disposed between two surfaces of the respective flat annular elements 27, 28 in coaxial position; the said elements are filled with granulated lead. The said chamber is surrounded by a jacket 29, provided with the insulating covering 25'. The bottom of the condenser 15 is connected by the pipe 30—30' through 20 an automatic regulator of the refrigeration 31—with the lower part of the evaporator 26; the latter is connected by the pipe 32 with the central suction chamber 4 of the compressor. The jacket 29 is supplied at 25 the top with the brine which is withdrawn from the chambers to be cooled through the conduit 33 by the pump 34 (which is always under operation) and is delivered to said jacket through the conduit 35. The brine 30 is again delivered to the rooms or chambers to be cooled, through the conduit 36 disposed at the lower part of the jacket 29. The 35 automatic regulator 31 for the flow of refrigerant and thereby the degree of cold 40 comprises a casing which is divided into two parts by an elastic diaphragm 37 having thereon a valve needle 38 which is adapted to close the inlet of the refrigerating liquid supplied by the pipe 30. The top chamber 39 communicating with the pipe 30' also 45 communicates with the pipe 30 leading to the evaporator. The second chamber 40 of the said apparatus is connected by the pipe 41 with a sleeve or jacket 42 surrounding 50 the pipe 32. The chamber 40, the tube 41 and the jacket 42 form a closed combination which contains a congealable liquid such as water.

The operation is as follows:

55 When the closed circuit comprising the compressor, condenser and evaporator is filled with fluid at the normal pressure, and when the said compressor is in operation, the latter will deliver the compressed fluid 60 through the conduits 20 and 18 into the condenser 15; said condenser is cooled by the water circulation 22, 23, 24 which also cools the compressor cylinders. The refrigerating fluid is condensed, and it is delivered 65 to the evaporator 26 through the conduit

30', the regulating device 31 and the conduit 30; the said fluid is withdrawn from the evaporator through the conduit 32 and enters then the compressor chamber 4. In this manner the liquefied cooling fluid will 70 evaporate in the evaporator 26, and it cools the brine proceeding from the cooled rooms or spaces through the conduit 33, the pump 34 and the pipe 35, the said brine being discharged in the cold state through the conduit 36 back towards the rooms or spaces to be cooled.

In order to reduce the said plant to the minimum size, I have provided the following details whereby a very active cooling 80 effect can be obtained in the said condenser and evaporator. The chambers of each of these devices are not empty, as in the known apparatus, but are filled with good heat conducting metallic substances such as granulated lead. In this manner the surface is contact with the cooling fluid is much increased. Further, each of said chambers is surrounded by a wire winding 15' 26' which is a good conductor of heat; this will considerably increase the outer surface of the 85 said heat exchanging devices, while at the same time a more active circulation of the liquid is obtained.

The operation of the said refrigerating regulator is as follows: When the cold conveying brine circulating in 29 round the evaporator 26 cannot take any more calores away from the refrigerating chambers, which occurs when latter are sufficiently cooled the said brine remains cold when it comes back to the channel 29 and will be still further cooled through the evaporation of the fluid contained in 26. At the same time latter fluid withdrawn by the compressor through the pipe 32 becomes colder and colder, making the water in the jacket 42 freeze upon a greater length; the volume of the total water and ice therein increases, whereby the diaphragm 37 is caused to ascend and to move the needle 38 against the opening of pipe 30. Thus the supply of liquefied refrigerating fluid to the evaporator 26 through said pipe 30 is gradually reduced to zero as the freezing of the water in the jacket 42 proceeds. Thereby the fluid circulates with greater slowness and gives away less cold. The brine will cease to become any colder and the needle will therefore not close any more when this state of equilibrium is attained. The cold created by the apparatus is thus reduced automatically to the amount sufficient for keeping down the temperature to the required degree. The production of cold can even be stopped entirely when it is unnecessary; in such a case the pipe 30 would be completely closed the volume of ice being maximum in the jacket 42.

The adjustment of this regulating device 130

- consists in making the mean opening position of the needle valve correspond to the volume of the congealable liquid, when it is frozen upon one-half the length of the jacket surrounding the suction pipe. In this manner, the apparatus will automatically regulate the operating rate so as to secure the maximum heat exchange in the evaporator.
- 10 As a secondary advantage, I am enabled to prevent all obstruction due to foreign bodies of small size, such as oxides dust, or small particles of water; in the case of an obstruction, the output will cease, and 15 therefore no more cold is brought to the pipe 32, so that the frozen liquid will melt, allowing the needle-valve to open and the foreign substances will thus escape into the evaporator.
- 20 Only in this latter case will the apparatus work intermittently.

What I claim is:

In a refrigerating apparatus comprising a compressor, a condenser, an evaporator,

connected to form a closed system, valve 25 mechanism controlling the flow of refrigerant from the condenser to the evaporator, said valve mechanism comprising a chamber, a diaphragm dividing said chamber, a needle directly secured to said diaphragm 30 and acting on one side of said diaphragm to control the flow of refrigerant to the evaporator, a closed tubular container surrounding the suction pipe leading to the compressor, and connected to said chamber 35 on the other side of said diaphragm, said container, connection, and chamber on the other side of said diaphragm being filled with water adapted to change from liquid to solid state and reversely by the change 40 in temperature of the refrigerant fluid passing to said compressor thru the suction pipe and thus to operate the needle thru the action of the diaphragm.

In witness whereof I have hereunto set 45 my hand.

PIERRE MAURICE JAUVERT.
